UNITED STATES PATENT OFFICE.

ROBERT A. MCKEE, OF MILWAUKEE, WISCONSIN, ASSIGNOR TO ALLIS-CHALMERS COMPANY,
OF MILWAUKEE, WISCONSIN, A CORPORATION OF NEW JERSEY.

BLADE-FASTENING.

No. 899,607.

Specification of Letters Patent. Patented Sept. 29, 1908.

Application filed February 13, 1907. Serial No. 357,113.

To all whom it may concern:

Be it known that I, ROBERT A. MCKEE, a citizen of the United States, residing at Milwaukee, in the county of Milwaukee and 5 State of Wisconsin, have invented certain new and useful Improvements in Blade-Fastenings, of which the following is a specification.

This invention relates to means for fastening blades to the spindles of steam turbines, 10 rotary pumps, air compressors, or similar machines designed either for acting upon a fluid, or being actuated by a fluid, the purpose of this invention being to provide a simple and strong fastening means for securing 15 a plurality of blades, or a plurality of rings of blades upon such a member in such a manner that the displacement of said blades by the centrifugal force developed is impossible. 20

On the drawings which accompany this specification and form a part thereof, and on which the same reference characters designate the same elements wherever they may 25 appear in the several views,—Figure 1 represents a steam turbine spindle, for example, in elevation, parts being shown in section, embodying this invention. Fig. 2 represents a steam turbine spindle similar in general 30 construction to that shown by Fig. 1 but illustrates a modification. Fig. 3 illustrates an elevation of a foundation ring with blades secured thereto. Fig. 4 illustrates a modification of the structure of the foundation 35 rings; and Fig. 5 illustrates a perspective of one of the holding rings.

The essential characteristics of this invention comprise a spindle or similar rotatable member upon which are mounted foundation rings in which blades are assembled, and these foundation rings are then locked by holding rings which prevent displacement or radial release of the blades and foundation rings from the spindle by the centrifugal 45 force developed by the blades during the rotation of the spindle.

Referring to the drawings, the numeral 1 designates the spindle of a steam turbine which is provided with the steps or stages 2, 50 3 and 4, said spindle being adapted to be mounted in a stator according to the ordinary custom, the type of spindle shown being a type belonging to the well known Parsons type of steam turbine. At the low pressure 55 end of each of the stages 2, 3 and 4, the spin-

dle is provided with a collar or projection 5, 6 and 7, respectively, while at the high pressure end of each of these stages the spindle is provided with screw threads, as indicated respectively by the numerals 8, 9 and 10. 60

The numerals 11, 12 and 13, designate rings which are adapted to be slipped over the body of the spindle and rest against the shoulders 7, 6 and 5, respectively.

The numeral 14 designates foundation 65 rings with which blades 15 are locked in any suitable manner, a foundation ring and the blades assembled therewith being adapted to be seated upon the spindle 1 against the rings 11, 12 and 13, respectively, and preferably the rings 11, 12 and 13 are undercut, as designated by the numerals 110, 120 and 130; and the foundation rings next adjacent thereto are provided with projections 16 which are adapted to engage within the recesses or undercut portions of said rings, 70 whereby the foundation rings and the blades carried thereby are held against outward displacement under the action of centrifugal force. The opposite side of a foundation 75 ring is provided with a projecting portion 17, and the holding ring 18 next adjacent thereto is provided with a recess 19, within which said projection 17 is adapted to be received, the opposite side of the holding ring 18 being 80 shaped to correspond to the corresponding side of the ring 11. It will thus be apparent that by assembling the rings 11, 12 and 13, and the foundation rings with the blades carried thereby, each foundation ring being included between two holding rings, that the foundation rings and blades carried thereby 85 are held within the recessed portions of the holding rings, whereby any tendency to move outward under the action of centrifugal force is prevented. 90

The numeral 20 designates holding rings which are formed similar in all respects to the holding rings 18, with the exception that one of the faces of each is preferably plain 95 instead of being undercut or provided with a projection, and against these plain faces the nuts 21, 22 and 23 which screw upon the screw-threaded portions 10, 9 and 8 of the spindle are adapted to seat, whereby the several foundation and holding rings may be pressed firmly together against the collars 5, 100 6 and 7.

The construction shown by Fig. 2 of the drawings is in all essential particulars the 110

same as that shown by Fig. 1, the difference being that the holding rings 11, 12 and 13 are omitted, the foundation rings 14 being received directly against the shoulders 50, 60 5 and 70, which are undercut to fit the adjacent face of the foundation rings.

Fig. 4 illustrates a modification of the structure of the foundation ring, the foundation ring being severed so as to divide it into 10 sections 140, 141, 142 and 143, the shroud 30 being similarly severed so that the foundation rings and blades carried thereby are composed of a plurality of segments, the method of assembling these segments upon 15 the spindle being in all substantial particulars the same as already described for the solid foundation rings.

It will be observed that in case the construction illustrated by Fig. 4 is adopted, the 20 entire strain due to centrifugal force will be thrown upon the holding rings, which is not the case where the foundation ring is a solid member.

What I claim is,—

25 1. The combination with a spindle, of a foundation ring seated thereon, blades locked to said foundation ring to deny relative radial release, by relative axial motion, an annular abutment on the spindle, and a 30 holding ring seated on the spindle and clamping said foundation ring against said abutment.

2. The combination with a spindle of a foundation ring seated thereon, said foundation 35 ring being provided with blades and with projections on opposite faces thereof,

and two holding rings also seated upon said spindle, one on either side of said foundation ring, said holding rings being provided with recesses within which the projections upon 40 said foundation ring are disposed.

3. The combination with a spindle, of a foundation ring seated thereon, blades locked to said foundation ring to deny relative radial release, by relative axial motion, 45 an annular abutment on the spindle, and a holding ring seated on the spindle and coacting with said abutment to lie adjacent to and to deny radial release of said foundation ring without relative axial displacement between said foundation ring and one of said adjacent restraining elements.

4. The combination with a spindle, of a row of blades provided with a foundation ring, and two restricting elements comprising 55 an annular abutment on said spindle adjacent said foundation ring of the row of blades and a holding ring seated on the spindle adjacent the foundation ring of the row of blades and, by relative axial motion between 60 said foundation ring of the row of blades and one of said adjacent elements, locking the said foundation ring of the row of blades to said abutment to deny radial release of the row of blades from the spindle. 65

In testimony whereof, I affix my signature in the presence of two witnesses.

ROBERT A. MCKEE.
